UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,824, dated October 29, 1895.

Application filed September 27, 1895. Serial No. 563,938. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

o The design consists of an arrangement of ornamental lines forming panels of Gothic style with a shield-like ornament having a Gothic form of ornament resting on the top of the shield ornament, and flowing ribbons 5 and small cross or sword shaped ornaments at each side of said shield ornament, as represented in the accompanying drawing.

The border of said design is also formed of ornamental lines forming panels of Gothic style with shield-like ornaments and Gothic 20 form of ornament resting on said shield ornaments and small sword-shaped ornaments and flowing ribbons on each side of said shield ornaments, as shown in the drawing.

What I claim is—

1. The design for wall paper herein shown and described.
2. In the design for wall paper the border herein shown and described.

Witness my hand this 24th day of September, 1895.

CHARLES BOOZ.
